CONTROL APPARATUS FOR INTERNAL-
COMBUSTION ENGINES

Leighton Lee, II, West Hartford, Conn., assignor,
by mesne assignments, to Niles-Bement-Pond
Company, West Hartford, Conn., a corporation
of New Jersey

Application June 29, 1945, Serial No. 602,282

21 Claims. (Cl. 123—119)

1

The present invention relates to apparatus for controlling the supply of fuel to internal combustion engines, and particularly to control apparatus for a fuel supply system of the type including a set of pumps for injecting liquid fuel into the individual cylinders of an internal combustion engine, or into the intake manifold near the individual ports of the cylinders.

An object of the present invention is to provide improved means for controlling the quantity of fuel pumped per stroke in such injection pump mechanism.

Another object is to provide improved apparatus for controlling such pump mechanism during starting of the engine.

Another object is to provide improved means for controlling such injection pump mechanism under idling or light-load conditions.

A further object is to provide, in injection pump control apparatus having two types of control mechanism, one for normal running, and the other for special operating conditions as starting or idling, improved mechanism for transferring control from one to the other of the two controlling devices.

A further object is to provide, in a fuel supply control system including a pump delivery control shaft and a shaft used during engine operating conditions as a mixture control shaft, a clutch between the two shafts, a spring biasing the clutch to engaged position and means responsive to the fuel pressure provided by an engine driven pump for releasing the clutch, so that the pump delivery may be manually controlled by the mixture control shaft when the engine is not running and so that the pump delivery control mechanism is released from the mixture control shaft as soon as the engine starts to run.

Another object of the present invention is to provide improved valve means for controlling a fluid motor in response to the relative positions of two control elements, so that the motor may be made to position one of the elements in accordance with the position of the other.

Other objects and advantages of the present invention will become apparent from a consideration of the appended specification, claims and drawings, in which

Figure 1 illustrates, somewhat diagrammatically, a fuel supply system for an internal combustion engine, including control apparatus embodying certain features of my invention.

Figure 2 is a somewhat diagrammatic illustration of a modified form of fuel supply control mechanism, including certain additional features

2

of my invention, as well as modified forms of certain of the features shown in Figure 1.

Figure 3 is a view taken along the line 3—3 of Figure 2, looking in the direction of the arrows,

Figure 4 is a view taken along the same line as Figure 3, but looking in the opposite direction, as indicated by the arrows 4—4 in Figure 2,

Figure 5 is a view of a selector valve shown in Figure 2, but with the parts in a different position,

Figure 6 illustrates a modified form of hydraulic motor which may be used in place of that shown in Figure 2, and

Figure 7 is a cross-sectional view taken along the line 7—7 of Figure 6.

Figure 1

There are shown in Figure 1 a portion of the air induction system of an internal combustion engine, a portion of the fuel supply system including injection pump mechanism and means for controlling the delivery of the injection pump mechanism. The delivery control means includes means responsive to the rate of air flow thru the air induction system, which controls the pump delivery under normal engine operating conditions. The pump delivery control mechanism also includes means for manually controlling the pump delivery when the engine is not running, as under starting conditions, and means for controlling pump delivery in accordance with the throttle position under idling or low load conditions.

Referring to Figure 1, there is shown an air conduit 10, thru which air flows from an entrance 12, past a venturi 14, and an air flow controlling throttle valve 16 to an outlet 18. From the outlet 18, the air usually passes thru a supercharger into the engine intake manifold. Such a supercharger is commonly used on aircraft engines, and the present fuel supply control system is particularly designed for use on aircraft engines, although its utility is not so limited. In some cases, a supercharger may also be used upstream from the entrance 12. According to the well-known laws of fluid flow thru a Venturi meter, a pressure differential is established between the entrance 12 and the throat of venturi 14, which pressure differential varies with the square of the velocity of the air flowing thru the venturi 14. This pressure differential is used to create a flow of air thru a secondary air passage which may be traced from a plurality of impact tubes 20 whose ends are open to the impact of the entering air, thru a conduit 22 interconnecting the

impact tubes 20, a boost venturi 24, a chamber 26, past a valve 28 and thru a conduit 30 to the throat of venturi 14.

The valve 28 is positioned by a flexible bellows 32, which forms one wall of an expandible sealed chamber 34. The chamber 34 is filled with a fluid having an appreciable coefficient of thermal expansion, so that the position of valve 28 varies in accordance with the pressure and temperature inside the bellows 32. If required, a suitable spring or springs may be added to cooperate with bellows 32 in positioning valve 28.

The valve 28 varies the flow thru the secondary air passage in accordance with the density of the air, so that the pressure differential between the entrance and throat of the boost venturi 24 varies substantially in accordance with the mass of air flowing per unit time thru passage 10, rather than in accordance with the velocity of the air flow. This density or altitude compensating effect is completely described and claimed in the copending application of Milton E. Chandler Serial No. 490,281, filed June 10, 1943, now Patent No. 2,393,144, issued Jan. 15, 1946, and assigned to the assignee of the present application.

The pressures at the entrance and throat of the boost venturi 24 are communicated thru conduits 36 and 38 respectively, to chambers 40 and 42, respectively, in a control valve unit generally indicated at 44.

The chambers 40 and 42 are separated by a flexible diaphragm 46. The control valve unit 44 also includes an expandible chamber 48 separated from the chamber 40 by a flexible diaphragm 50, and an expandible chamber 52 separated from chamber 42 by a flexible diaphragm 54. The diaphragms 50, 46 and 54 are connected at their centers to the stem 56 of a valve 58.

Fuel for the engine comes from a tank (not shown) and flows thru a conduit 60, a boost pump 62, usually driven by an electric motor, a transfer pump 64, usually engine driven, thru a conduit 66, past an idle valve 68, thru a jet system and mixture control unit generally indicated at 70, a conduit 72, a recirculating venturi 74, a conduit 76, a vapor trap 78, a conduit 80, to a fuel injection pump generally indicated at 82. Fuel from the pump 82 flows thru a plurality of conduits, one of which is shown at 84, to the cylinders of the engine.

The pump 82 is of more or less conventional design, and includes a plurality of plungers, one for each engine cylinder. One of the plungers is shown at 86 and is reciprocated by a cam 88 driven by the engine. The plunger 86 may be rotated by means of a rack 90 which engages a pinion 92 on the plunger. The plunger 86 is provided with a contoured recess in its lateral surface which cooperates with an inlet port 94 and a spill-over port 96. The angular position of the plunger 86 in its associated cylinder determines the point in the travel of the plunger at which the closure of inlet port 94 takes place. The spill-over port 96 is always opened at the same point in the plunger travel. When either of these ports is opened, the pressure ahead of the plunger is relieved, and no pumping action thru the check valve 85 to conduit 84 takes place. When both ports are closed and the plunger is moving toward the right, the pumping action takes place. Therefore, rotation of the plunger 86 by the rack 90 determines the quantity of fuel pumped per stroke of the plunger. Fuel discharged thru the spill-over port 96 passes thru a conduit 98, a vapor trap 100 and a conduit 102

to the throat of the recirculating venturi 74. The purpose of the recirculating venturi and the vapor trap 100 is to make sure that all vapor bubbles are removed from the fuel after its turbulent passage thru the spill-over port before it is again supplied to the pump inlet.

The jet system and mixture control 70 includes a fixed restriction 104, a fixed restriction 106, a restriction 108 controlled by a valve 110 biased to closed position by a spring 112, and a restriction 114 controlled by a valve 116, which is biased open by a spring 118 and closed by a cam 120 on a mixture control shaft 122. The end of shaft 122 also carries a ported sleeve 124 which cooperates with a ported seat 126, and which may be used to cut off the flow of fuel to the conduit 72. The shaft 122 may be positioned by a suitable manual lever 123.

When the mixture control shaft 122 is in the position illustrated, fuel may flow only thru restriction 104. If the fuel pressure differential across the jet system 70 is high enough, valve 110 will open, allowing an additional flow of fuel. The valve 110 is therefore termed an enrichment valve.

The shaft 122 may be rotated to a position where the cam 120 allows valve 116 to open under the influence of spring 118. This is known as the rich position of the mixture control, since fuel can then flow thru both restrictions 104 and 114. In both the positions of the mixture control so far described, the ports of the sleeve 124 and the seat 126 are aligned so that the cut-off valve does not restrict the flow of fuel to the engine.

For a given area of the metering restriction open to the flow of fuel, the pressure differential across the jet system 70 is a measure of the rate of flow of fuel to the engine. The pressure in the fuel line at the upstream side of the jet system is communicated thru conduit 132, a chamber 134, a conduit 136, a restriction 138, and a conduit 140 to the chamber 52 of the control valve unit 44. Fuel pressure at the downstream side of the jet system is communicated thru a conduit 142 and a restriction 144 to the chamber 48 of the valve control unit 44.

From the foregoing, it may be seen that an air pressure differential acts downwardly on diaphragm 46 with a force which is a measure of the mass of air flowing to the engine per unit time. At the same time, the fuel pressure differential across the jet system acts on diaphragms 54 and 50. Since the fuel pressure under diaphragm 54 is higher than the pressure above diaphragm 50, the fuel pressure differential provides a net upward force. Under steady conditions, these two forces are balanced, indicating that the fuel flow is proportioned to the air flow, and valve 58 remains in the central position indicated in the drawing.

The position of rack 90 which controls the delivery of the injection pump 82 is determined by a gear 146 engaging rack 90 and fixed on shaft 148. The shaft 148 is rotated by a fluid servomotor generally indicated at 150. Motor 150 includes a piston 152 reciprocating in a cylinder 154 and separating two opposed expandible chambers 156 and 158 formed between the piston and the opposite ends of the cylinder. The piston 152 is connected by a rod 160 to a crank arm 162 attached to shaft 148.

Shaft 148 carries a clutch member 164, which is notched as in 166 to receive a tooth or projection 168 on a shiftable clutch member 170.

Tooth 168 is longer than the travel of member 170, so that it is always engaged with notch 166. The opposite end of member 170 carries a projection 172 which is movable into engagement with a notch 174 formed in a helical gear 176 which is freely rotatable on the shaft 148. The gear 176 mates with a gear 178 fixed on the mixture control shaft 122. The shiftable clutch member 170 is movable by means of a shifting lever 178 pivoted at 180 and having its opposite end pivotally connected to a rod 182. The rod 182 is provided with a crater in its opposite end. In this crater rides a conical tip formed on the end of a valve stem 187. The stem 187 is attached to the center of a diaphragm 184. A spring 186 holds the rod 182 against stem 187. The right side of diaphragm 186 is exposed to the pressure in chamber 134, which is the same as the fuel pressure on the upstream side of the jet system. The spring 186 biases the diaphragm 184 for movement to the right against the pressure in chamber 134. The chamber at the left of diaphragm 184 is vented to atmosphere thru the aperture around stem 182. If a time delay in the motion of diaphragm 184 is desired, it may be provided and controlled by properly designing the vent aperture.

Operation of Figure 1

When the parts are in the positions shown in the drawing, the engine is running, and the fuel pressure in chamber 134 has moved the diaphragm 184 to the left, compressing the spring 186 and tilting the lever 178 so as to move projection 172 out of the notch 174. Therefore, rotation of mixture control shaft 122 turns the gear 176 freely on shaft 148 and does not affect the position of the pump delivery control rack 90.

When the engine stops, the pump 64 stops and the fuel pressure in chamber 134 consequently drops until it can no longer overcome the spring 186, which thereupon moves diaphragm 184 to the right and moves the shiftable clutch member 170 to the left engaging the projection 172 with notch 174. If the tooth 172 and notch 174 are not aligned, they can be aligned by manual movement of the mixture control lever 123 until the tooth snaps into the notch. Rotation of mixture control shaft 122 then causes gear 176 to rotate the clutch member 170 and the clutch member 164, and the latter being fixed on the shaft 148, the shaft rotates also, changing the position of the pump capacity control rack 90. At the same time, a valve 188, attached to the center of diaphragm 184, is moved to the right, opening a by-pass connection between chambers 156 and 150. This by-pass connection may be traced from chamber 156 thru conduits 190, 192 and 194, past valve 188 and thru conduit 196 to chamber 158. This by-pass connection prevents a hydraulic locking of the piston 152, making the piston easily movable with the shaft 148 as the latter is manually moved by the rotation of mixture control shaft 122.

The pressure at the discharge side of boost pump 62 is regulated by a relief valve generally indicated at 59, biased to closed position by a spring 61 whose strength determines the boost pump discharge pressure. The discharge pressure of the transfer pump 64 is controlled by a relief valve generally indicated at 65, biased to closed position by a spring 67. The spring 67 of the relief valve 64 is made stronger than the spring 61 of relief valve 59, so that when the en-

gine driven pump 64 is running, the pressure at its discharge outlet is greater than when only the boost pump 62 is running. The two springs 61 and 67 are so coordinated with spring 186 of the clutch controlling mechanism that the clutch will not be operated to release the pump delivery control shaft 148 from the mixture control shaft 122 when the only fuel pressure is that supplied by the boost pump. When the engine driven pump 64 starts to run, the pressure increases to the higher value determined by spring 67, which provides a sufficient force acting on diaphragm 184 to compress spring 186 and operate the clutch mechanism. As previously pointed out, a time delay may be provided to prevent diaphragm 184 from operating the clutch on a sudden pressure surge, thus ensuring that the engine is running steadily before the clutch is operated.

20 The pumps 62 and 64 are provided with bypass valves 68 and 69, respectively, which allow fuel to be pumped past either one of the pumps by the other pump, if the one pump is not running.

25 With the engine running, if the air flow increases, the increased pressure differential acting on diaphragm 46 move the valve 58 downwardly, thereby allowing fuel to flow from the downstream side of the jet system thru conduit 142, restriction 144, conduits 198 and 200, past the valve 58 and thru a conduit 202 to chamber 156. At the same time, chamber 158 is connected thru a conduit 204, past valve 58 to a drain conduit 206 which leads to the fuel intake conduit 60. Therefore a pressure differential is established on piston 152, causing the latter to be moved to the left, rotating shaft 148 clockwise, moving the rack 90 downwardly. This rotates the pinion 92 and plunger 86 so as to increase the delivery of the pump 82, thereby increasing the fuel flow.

30 Motion of the piston 152 to the left continues until the fuel flow has increased sufficiently so that the fuel pressure differential acting upwardly on valve 58 balances the downwardly acting air pressure differential.

35

40 The lower end of valve 58 is subject to the same pressure as the upper end of stem 56, this pressure being supplied thru the lower end of valve 58 thru conduits 198 and 208. This makes 45 the net diaphragm area subject to the downward pressure in chamber 48 equal to the net diaphragm area subject to the upward pressure in chamber 52.

45 If for any reason the fuel pressure differential exceeds the air pressure differential, the valve 58 is moved upwardly. Fuel then flows from the upstream side of the jet system thru the conduit 132, chamber 134, conduit 136, restriction 138, conduit 210, past valve 58 and thru conduit 204 into chamber 158. At the same 50 time, chamber 156 is connected thru conduits 190 and 202, past valve 58 to drain conduit 206. A pressure differential is thereby applied to piston 152 which moves it to the right, thereby rotating shaft 148 counter-clockwise and moving the 55 pump delivery control rack 90 in a delivery decreasing direction. This movement continues until the fuel flow has decreased by an amount sufficient so that the fuel pressure differential again balances the air pressure differential and 60 valve 58 is restored to its neutral position.

65 The restrictions 136 and 144 provide a means for anticipating the response of the pump capacity control to the movements of the control valve 70 58 so as to restore the valve 58 to its normal posi-

tion more quickly, thereby preventing over-shooting and hunting of the control system. For example, when the valve 58 moves downwardly, fuel flows thru the restriction 144 to the chamber 156. This produces a drop in pressure on the left hand side of the restriction 144, thereby decreasing the pressure in chamber 48. The force due to the fuel pressure differential acting upwardly on valve 58 is thereby increased before the actual pressure differential across the jet system 70 is increased by the action of the pump delivery control mechanism.

Similarly, when the valve 58 is moved upwardly, in a fuel flow decreasing direction, the fuel supplied to the servo-motor 150, flows thru restriction 138, thereby reducing the pressure in chamber 52 in proportion to the rate of flow thru restriction 138. This reduction in pressure in chamber 52 anticipates the final reduction in the fuel pressure differential which will result from the operation of the servo-motor 150, and therefore operates to dampen the response of the system and to prevent hunting and over-shooting.

It has been found that the valve 58 is more sensitive and provides a better control when the lands which cover the ports leading to conduits 202 and 204 are made just slightly smaller than those ports. However, under such conditions there will be a slight leakage thru the valve 58 to the drain passage 206 at all times. Since this leakage might come from either the upstream or downstream side of the jets, it might upset the fuel metering of the system. To avoid upsetting the fuel metering, while retaining the desired sensitivity of the valve, I have provided a small leakage restriction 212 in the conduit 192 which leads from chamber 134 to conduit 190. Thru the restriction 212, a small amount of fuel at high pressure is continuously supplied to chamber 156. This tends to move the servo-motor piston 152 in a fuel flow increasing direction, and as a result, the control valve 58 establishes its normal position at a point where the conduit 202 is provided with a slight leakage space to the drain conduit 206. This allows the high pressure fuel supplied thru restriction 212 to pass out to the drain conduit 206 without disturbing the position of the piston 152.

Under low air flow conditions, such as are encountered at idling and low engine loads, the air pressure differential applied to diaphragm 46 may not be an accurate measure of the air flow, because of the large area of the passage 10 as compared to the small quantity of air then flowing. Under such conditions, it is necessary that additional means be provided to regulate the fuel flow. The means provided are the idle valve 68, which is connected to the throttle to operate concurrently therewith and the spring 49, which acts on the valve 58 in a fuel flow increasing direction. The spring 49 is chosen so that its force is small as compared to the forces due to the air and fuel pressure differentials which act on the valve 58 under normal running conditions. The effect of spring 49 is then negligible. However, under low air flow conditions, the force acting downwardly on diaphragm 46 practically disappears, so that the force of spring 49 becomes the predominating force controlling the valve 58. It tends to move the valve in a fuel flow increasing direction. At the same time, the valve 68 is moved toward closed position as the throttle approaches its closed position. The contour of valve 68 and the strength of spring 49 may be selected to give any desired variation of fuel-to-air ratio with throttle position under idling conditions. As soon as the

throttle moves out of the range of positions near its closed position, the valve 68 is retracted so that it no longer obstructs the fuel flow.

There is shown in Figure 2 a modified form of fuel injector pump delivery control mechanism. In Figure 2, those elements which correspond fully to their counterparts in Figure 1 have been given 10 the same reference numerals, while elements which have no counterparts in Figure 1 have been given new reference numerals in the 300 to 599 series.

The air induction and measuring system of Figure 2 corresponds generally to that of Figure 1. There is shown an air induction passage 10, a density compensating valve 26, and a fixed restriction 302 which replaces the boost venturi 24 of Figure 1. The control valve unit 44 corresponds 20 generally to the control valve 44 of Figure 1.

The pump 64 of Figure 2 is provided with a relief valve 304 which cracks open slightly at low pump discharge pressure against a weak spring 306. However, in order to open sufficiently to pass 25 any appreciable quantity of fuel, the pump discharge pressure must overcome a stronger spring 308. The purpose of this dual spring arrangement will be described later.

Fuel flows from the pump 64 in Figure 2 thru 30 a conduit 310 thru a mixture control 312, conduits 314 and 316, a jet system 318 and thence thru a conduit 320 to a number of fuel injection pumps, one of which is shown at 82.

The mixture control 312 includes a disc valve 322 fixed on a shaft 324. When the valve 322 is in the full line position shown in the drawing, fuel can flow only thru the conduit 314 to the jet system 318. When the valve 322 is in the dotted line position, fuel can flow thru either of the conduits 40 314 and 316. The full line position is known as the lean position of the mixture control and the dotted line position is known as the rich position. The mixture control is operated by a lever 313 attached to shaft 324, and may also be moved 45 to a cut-off position wherein fuel cannot flow thru the conduits 314 and 316.

Fuel passing thru the conduit 314 may flow either thru a fixed restriction 326 or a restriction 328 controlled by a valve 330, which is biased 50 to closed position by a spring 332. Fuel passing thru conduit 316 flows thru a restriction 334. The fuel passing thru the restrictions 328 and 334 must also pass through a fixed restriction 336. Restriction 326 corresponds to restriction 102 of Figure 1. Restriction 336 corresponds to restriction 106 of Figure 1. Restriction 328 and valve 330 correspond to restriction 108 and valve 110 of Figure 1. Restriction 334 corresponds to restriction 114 of Figure 1. The valve 322 performs both 55 the functions of valves 116 and 124 of Figure 1, since it may selectively open and close the conduit thru restriction 334 just as valve 116 selectively opens and closes the path of fuel flowing thru restriction 114 of Figure 1. It may also operate to completely cut off the fuel, similarly to the cut-off action of valve 124 of Figure 1.

A cam 338 on the throttle shaft 340 cooperates with a follower 342 on a crank arm 344 attached to shaft 346. A helical gear 348 is fixed on the shaft 346 and cooperates with another helical gear 350 fixed on a sleeve 352 surrounding an extension of the mixture control shaft 324. The sleeve 352 and shaft 324 are confined between upper and lower castings 354 and 356.

At its end opposite the gear 350 the sleeve 352

carries a valve member 358, which is drilled to provide diametrically spaced ports 360 and 362 opening in its vertical face. The port 360 is connected thru a passage 364 drilled thru the sleeve 376 to a port which opens into an annular recess 366 formed in the castings 354 and 356. The port 362 is connected thru a passage 368 drilled in sleeve 376 to a similar annular recess 370 formed in the castings 354 and 356. The recesses 366 and 370 are connected to conduits 372 and 374, respectively. Beyond the valve member 358, another sleeve 376 surrounds the shaft 324. At its left end, the sleeve 376 carries a valve member 378 having a face which slidingly engages the face of the valve member 358. The face of valve 378 is provided with a pair of spaced arcuate grooves 380 and 382. The groove 380 communicates with a passage 384 drilled thru the sleeve 376 and leading to an annular recess 386 formed in the castings 354 and 356. The groove 382 communicates with a passage 388 drilled thru the sleeve 376, which leads to the upper end of a cylinder 390 formed in the castings 356 and 354. A passage 392 connects the annular recess 386 with the lower end of the cylinder 390. A piston 394 reciprocates within the cylinder 390 and separates it into upper and lower chambers 396 and 398. The piston 394 and the cylinder 390 together form a fluid servo-motor generally indicated by the reference character 400. The piston 394 is attached to a rod 402 connected thru a link 404 to a crank arm 406 attached to the sleeve 376.

A chamber 408 is formed in the castings 354 and 356. Inside the chamber 408, the sleeve 376 carries a helical gear 410, which mates with another helical gear 412 fixed on a shaft 414. The shaft 414 also carries a gear 416 which engages with and positions the delivery control rack 90 of the injector pump 82.

The servo-motor 400 is operated by fuel under pressure, which is taken from the main fuel conduit 310 thru a branch conduit 418. The servo-motor 400 may be controlled either by the control valve unit 44 or by the valve members 358 and 378, depending upon the position of a selector valve mechanism generally indicated at 420. The selector valve mechanism 420 includes a diaphragm 422 separating a pair of expandable chambers 424 and 426 and attached at its center to a spool valve 428. The diaphragm 422 is also connected to the center of a spring disc 430. A compression spring 432 is retained between the spring disc 430 and the left hand end of the casing 434 in which the diaphragm 422 is mounted. The spring disc 430 is provided to give a snap action of the diaphragm and valve 428 between the position shown in the drawing hereinafter referred to as the "air flow controlled" position and another position wherein the valve 428 blocks the passage of fuel between conduits 464 and 466, and between conduits 468 and 470, which other position is hereinafter referred to as the "throttle controlled" position. Chamber 426 is connected thru a conduit 436 and conduit 418 to the fuel line on the upstream side of the jet system. The chamber 424 is connected thru conduits 438 and 440 to the fuel line on the downstream side of the jet system.

The right end of shaft 324 is slotted, as shown at 442, and the right end of sleeve 376 is slotted at diametrically opposite points, as illustrated at 444. A plate 446 carried by a disc 448 rides in the slot 442, and may be moved to the left from the position shown in the drawing so as to also

engage the slot 444, thereby coupling the shaft 324 and the sleeve 376 to rotate together. The disc 448 is connected thru a coupling shown diagrammatically at 450 to a diaphragm 452. The coupling 450 may be of any suitable type which will permit rotation of the disc 448 relative to the diaphragm 452. The diaphragm 452 separates a pair of expandable chambers 454 and 456. A spring 458 in the chamber 456 biases the diaphragm in a direction to cause plate 446 to engage both slots 442 and 444. The chamber 456 is vented to atmosphere, as shown at 460. The size of the vent 460 may be controlled as desired to give the clutch mechanism a time delay characteristic. The chamber 454 is connected thru a conduit 462 to conduit 418 containing fuel at high pressure. When the engine is running, the pressure in chamber 454 is sufficient to overcome spring 458 and move the diaphragm 452 and plate 446 to the position shown in the drawing, so as to disengage plate 446 from slot 444, whereby the shaft 324 and the sleeve 376 may then rotate relative to each other.

Operation of Figure 2

When the parts are in the positions shown in the drawing, the engine is running, and the fuel pressure in chamber 454 has compressed the spring 458 to release the plate 446 from engagement with slots 444 on the sleeve 376. The fuel pressure differential across the jet system acting on the diaphragm 422 is sufficient to hold valve 428 in the position shown, wherein the control valve unit 44 is in control of the servo-motor 400. If the air flow now increases, the force acting on diaphragm 46 of the control valve unit 44 increases moving valve 59 to the right. This allows fuel at high pressure to flow from conduit 418 thru valve 59, conduit 464, past valve 428, thru conduit 466 and passage 392 to the chamber 396 below piston 394. At the same time, the chamber 396 above piston 394 is connected thru a conduit 468, past valve 428, thru a conduit 470, past valve 59 and thru a conduit 472 to drain conduit 474. Therefore a fluid pressure differential is applied to the piston 394 in a direction to move it upwardly, thereby rotating the sleeve 376 to operate the pump delivery control mechanism thru the gears 410, 412 and 416 in a delivery increasing direction. This movement continues until the fuel pressure differential across the jet system has increased sufficiently to restore the valve 59 to its neutral position as shown in the drawing. If the air flow decreases, the control valve unit 44 operates to connect chamber 396 to the high pressure conduit 418 and chamber 398 to the drain conduit 474. This causes a downward movement of a piston 394 to operate the pump delivery control in a decreasing direction. If it is assumed that the throttle 16 is moved toward closed position and that the fuel pressure differential decreases correspondingly until the force acting on diaphragm 422 is not sufficient to maintain the spring disc 430 in the position illustrated, then the disc 430 snaps to a new position, shown in Figure 5, moving the valve 428 to a position where it blocks the flow between conduits 464 and 466 and also between conduits 468 and 470, but opens paths of flow between conduits 436 and 372 and between conduits 374 and 474. The servo-motor 400 is then controlled by the valve members 358 and 378. The valve member 358 is positioned by the throttle, and the operation of these two valve members is such that the

valve member 378 is driven by the servo-motor until it reaches an angular position corresponding to that of valve 358, which depends upon the position of throttle 16 and the contour of cam 338. When the parts of valve 28 are in the positions shown in Figure 5, fuel at high pressure will flow from conduit 418 thru conduit 436, chamber 426, conduit 372, recess 366, passage 364, groove 380, passage 384, recess 386, and conduit 392 to chamber 398 below piston 394. At the same time, chamber 396 above piston 394 is connected thru passage 388, groove 382, passage 368, recess 370, conduit 374, past valve 428, to drain conduit 414. Therefore the pump delivery control mechanism is operated in a delivery increasing direction, and the sleeve 376 is rotated in a counter-clockwise direction as viewed from its right end. This motion of piston 394 and sleeve 376 continues until the lands between the ends of grooves 380 and 382 and valve member 378 are aligned with the ports 360 and 362 in the valve member 358. When this occurs, the fuel passages to both chambers 396 and 398 of the servo-motor are blocked and it stops.

It may be seen that when the engine is running in the normal range of power output conditions that the fuel pressure differential is determined by the air pressure differential. Therefore, the point at which the selector valve mechanism 420 operates to shift control of the servo-motor 400 from the control valve unit 44 to the valve members 358 and 378 is determined by the rate of flow of air to the engine. On the other hand, the point at which the selector valve mechanism moves in the opposite direction is determined by the throttle position and by the cam 338 rather than by the rate of air flow. By properly contouring the cam 338, it is possible to insure that the selector valve mechanism 420 will not shift from its throttle controlled position to its air flow controlled position until the air flow has increased to a point where the fuel pressure differential thereafter established by the air flow control valve unit 44 will be sufficient to maintain the selector valve in its air flow controlled position. Likewise, it can be assured that the selector valve will not shift from its air flow controlled position to its throttle controlled position until the throttle has moved far enough toward closed position that the selector valve mechanism will thereafter stay in its throttle controlled position until the throttle is again opened. It has been found that by proper contouring of the cam 338, the change-over may be made to take place at substantially the same value of air flow in both directions. This mode of operation is aided by the well-known characteristics of a snap action mechanism such as the spring disc 430 by which such devices require a smaller force to maintain them in their snaped position than they require to move them to that position.

When the engine is not running, the spring 458 moves the plate 446 to the left. Thereafter, the fuel pump delivery may be controlled by positioning the mixture control shaft 324, provided that the shaft 324 is first rotated back and forth as required to line up the slot 444 with the plate 446. The selector valve mechanism at such times will be in the position where the valve members 358 and 378 control the servo-motor 400. At such times, movement of the sleeve 376 by the mixture control shaft 324 will operate the piston 394 as a pump. It may be seen that the valve members 358 and 378 will give a detent action when the ports 360 and 362 are lined up with the

grooves 380 and 382, since they will then block the flow of fuel pumped by the servo motor 394. By this means the pilot may know where the injector pump delivery control is set with respect to the throttle 16 and the cam 338. If the cam 338 is contoured to give the most efficient engine operation for a given throttle position, the pilot can tell by the detent action whether the injector pump delivery is being set leaner or richer than the most efficient position. If the detent action is found to be too severe, so as to prevent manual adjustment of the pump delivery control, it can be avoided by moving the throttles one way or the other when the detent action is encountered. This throttle movement will change the alignment between the ports 360 and 362 and the grooves 380 and 382 to eliminate the detent action.

The pump 64 is provided with a relief valve 304 which opens a short distance against a light spring 306 so that when the pump delivery control is being manually positioned the pressure established by the pumping action of the servo-motor piston 394 is relieved thru that valve, thereby preventing a hydraulic locking of the movement of the pump delivery control.

Figures 6 and 7

I have shown in Figures 6 and 7 a modified form of hydraulic servo-motor which may be used in place of that shown in Figure 2. This servo-motor is a gear type motor comprising a pair of mating gears 500 and 502. Fluid is supplied to and withdrawn from this motor thru passages 388 and 392, which correspond fully to the passages bearing the same reference characters in Figure 2. The flow of fluid thru these passages is controlled by the valve members 358 and 378. The valve member 378 is driven by the gear motor 500, 502. Both the valve members and the gear motor are capable of continuous rotation in either direction. Therefore, it may be seen that this type of valve mechanism and motor may be readily applied to any type of hydraulic control system where continuous rotation of the controlling or controlled devices, or both, is required. While I have shown and described certain preferred embodiments of my invention, other modifications thereof will readily occur to those skilled in the art, and I therefore intend my invention to be limited only by the appended claims.

I claim as my invention:

1. A fuel supply system for an internal combustion engine, comprising injector pump mechanism, means for controlling the delivery of said pump mechanism, motor means for operating said delivery controlling means, a manually movable control device, clutch means selectively movable between a first position wherein said manual control device is connected to said delivery controlling means and a second position wherein said device and said controlling means are independently movable, spring means for biasing said clutch means toward said first position, and means responsive to operation of said engine for moving said clutch means to said second position.

2. A fuel supply system for an internal combustion engine, comprising means for controlling the rate of fuel supply to said engine, motor means for operating said control means, a manually movable control device, clutch means for connecting said manual control device to said fuel supply controlling means, and means responsive to operation of said engine for operating said

clutch means to disconnect said control device from said fuel supply controlling means.

3. A fuel supply system for an internal combustion engine, comprising a fuel pump driven by said engine for supplying fuel under pressure, means for controlling the rate of fuel supply to said engine, motor means for operating said control means, a manually movable control device for operating said control means under starting conditions, clutch means for connecting said device and said fuel supply controlling means, and means responsive to the pressure of the fuel discharged by said pump to operate said clutch means to disconnect said device from said fuel supply controlling means.

4. A fuel supply system for an internal combustion engine, comprising injector pump mechanism, means for controlling the delivery of said pump mechanism, motor means for operating said delivery controlling means, a manually movable control device, clutch means selectively movable between a first position wherein said manual control device is connected to said delivery controlling means and a second position wherein said device and said controlling means are independently movable, said delivery controlling means being operable throughout substantially its entire range of movement by said manual control device when said clutch means is in its first position, and means for operating said clutch means.

5. A fuel supply system for an internal combustion engine, comprising means for controlling the rate of fuel supply to said engine, motor means for operating said control means, a manually movable control device, clutch means for connecting said manual control device to said fuel supply controlling means, said fuel supply controlling means being operable throughout substantially its entire range of movement by said manual control device when connected thereto by said clutch means, and means for operating said clutch means.

6. A fuel supply system for an internal combustion engine, comprising a first fuel transfer pump for supplying fuel to said engine, electric motor means for driving said first pump to supply fuel when the engine is stationary, first relief valve means for regulating the discharge pressure of said first pump at a first predetermined value, a second fuel transfer pump driven by said engine for supplying fuel thereto, second relief valve means for regulating the discharge pressure of said second pump at a second predetermined value greater than said first value, injector pump mechanism for supplying fuel to the cylinders of said engine, conduit means for conveying fuel from said first and second pumps to said injector pump mechanism, means for controlling the delivery of said injector pump mechanism, reversible motor means for operating said delivery controlling means, means responsive to the rate of flow of combustion air to said engine for controlling said reversible motor means, a manually movable control device, clutch means selectively movable between a first position wherein said manual control device is connected to said delivery controlling means and a second position wherein said device and said delivery controlling means are independently movable, means movable concurrently with said clutch means to interrupt control of said reversible motor means by said air flow responsive means when said clutch means is in said first position, spring means to bias said clutch means toward said first position, and means responsive to the pressure of the fuel

supplied to said injector pump mechanism thru said conduit means and effective when said fuel pressure exceeds said second predetermined value to overcome said clutch biasing spring means and move said clutch means to said second position.

5. A fuel supply system for an internal combustion engine, comprising a conduit for fuel flowing toward said engine, metering restriction means in said conduit, means for varying the pressure differential across said restriction means to vary the flow of fuel therethru, manual control means for varying the cross-sectional area of said restriction means, and clutch means for connecting and disconnecting said manual control means and said pressure differential varying means, said manual control means and said pressure differential varying means being independently movable over substantially their entire ranges of movement when said clutch means is disengaged, and said pressure differential varying means being movable by said manual control means over substantially its full range of movement when said clutch means is engaged.

7. A fuel supply system for an internal combustion engine, comprising injector pump mechanism for supplying fuel to the cylinders of said engine, a fuel conduit for conveying fuel to said injector pump mechanism, a metering restriction in said conduit, means for varying the delivery of said pump mechanism, a fluid motor for operating said pump delivery varying means including two expandable chambers separated by a movable wall, a valve responsive to the fuel pressure differential across said metering restriction for controlling the flow of fluid to said chambers, said valve being effective upon an increase in said fuel pressure differential to connect one of said chambers to said fuel conduit on the upstream side of said restriction and to connect the other chamber to 40 a drain, and upon a decrease in said fuel pressure differential to connect said other chamber to the fuel conduit on the downstream side of said restriction and to connect said one chamber to the drain, and a passage including a fixed restriction extending from the fuel conduit on the upstream side of said metering restriction to said other chamber so that under equilibrium conditions all fuel passing thru the valve to the drain is supplied from the upstream side of the metering restriction.

9. A fuel supply system for an internal combustion engine, comprising injector pump mechanism for delivering fuel to the cylinders of said engine, means for controlling the delivery of said pump mechanism, motor means for operating said delivery controlling means, a conduit for combustion air flowing to said engine, means for measuring the flow of combustion air thru said conduit, throttle means for controlling the flow of air thru said conduit, first motor control means operated by said air flow measuring means, second motor control means operated concurrently with said throttle means, and selector means responsive to the rate of flow of fuel to said engine for selectively placing said first and second motor control means in control of said motor means.

10. A fuel supply system for an internal combustion engine, comprising injector pump mechanism for delivering fuel to the cylinders of said engine, means for controlling the delivery of said pump mechanism, motor means for operating said delivery controlling means, a conduit for combustion air flowing to said engine, means for measuring the flow of combustion air thru said conduit, throttle means for controlling the flow of

15

air thru said conduit, a conduit for fuel flowing to said pump mechanism, a metering restriction in said fuel conduit, first motor control means responsive to said air flow measuring means and to the fuel pressure differential across said metering restriction and effective to control said motor means and thereby the delivery of said pump mechanism to maintain said fuel pressure differential substantially proportional to the rate of air flow, second motor control means, cam means movable with said throttle means for operating said second motor control means, selector means movable between first and second positions wherein said first and second motor control means, respectively, are in control of said motor means, snap action spring means associated with said selector means for biasing the same toward said second position, and a diaphragm subject to said fuel pressure differential for operating said selector means in opposition to said spring means, said spring means being effective when said fuel pressure differential falls below a predetermined value to move said selector means to said second position, and retain it there until said pressure differential increases to a substantially higher value, said cam means being contoured to cause an increase in the delivery of said pump mechanism and thereby an increase in said fuel pressure differential at a throttle position generally corresponding to an air flow just greater than that corresponding to the said predetermined value of fuel pressure differential.

11. A fuel supply system for an internal combustion engine, comprising injector pump mechanism for delivering fuel to the cylinders of said engine, means for controlling the delivery of said pump mechanism, motor means for operating said delivery controlling means, a conduit for combustion air flowing to said engine, means for measuring the flow of combustion air thru said conduit, throttle means for controlling the flow of air thru said conduit, first motor control means operated by said air flow measuring means, second motor control means operated concurrently with said throttle means, selector means for selectively placing said first and second motor control means in control of said motor means, a manually movable control device, clutch means selectively movable between a first position wherein said manual control device is connected to said delivery controlling means and a second position wherein said device and said controlling means are independently movable, spring means for biasing said clutch means toward said first position, and means responsive to operation of said engine for moving said clutch means to said second position.

12. A fuel supply system for an internal combustion engine, comprising injector pump mechanism for delivering fuel to the cylinders of said engine, means for controlling the delivery of said pump mechanism, fluid motor means for operating said delivery controlling means, a conduit for combustion air flowing to said engine, means for measuring the flow of combustion air thru said conduit, throttle means for controlling the flow of air thru said conduit, first control valve means operated by said air flow measuring means, second control valve means operated concurrently with said throttle means, selector means for selectively placing said first and second control valve means in control of said motor means, a manually movable control device, clutch means selectively movable between a first position wherein said manual control device is connected to said

16

delivery controlling means and a second position wherein said device and said controlling means are independently movable, spring means for biasing said clutch means toward said first position, and means responsive to operation of said engine for moving said clutch means to said second position, said second control valve means comprising cooperating valve members which block the passage of fluid thru said motor means at corresponding positions of said motor means and said throttle, said blocking of the fluid providing a detent action when said controlling means is operated by said manually movable control device.

13. A fuel supply system for an internal combustion engine, comprising injector pump mechanism for delivering fuel to the cylinders of said engine, means for controlling the delivery of said pump mechanism, fluid motor means for operating said delivery controlling means, means including a first hollow shaft connecting said motor means and said delivery controlling means, a throttle for controlling the flow of combustion air to said engine, a second hollow shaft aligned with said first shaft, and connected to said throttle for concurrent movement therewith, cooperating valve members connected to said first and second shafts for controlling said motor means to cause said first shaft to follow the movements of said second shaft, a manually rotatable shaft extending thru both said hollow shafts, and clutch means for connecting said manually rotatable shaft to said first hollow shaft so that the delivery of said pump mechanism may be manually controlled.

14. A fuel supply system for an internal combustion engine, comprising injector pump mechanism for supplying fuel to said engine, means for controlling the delivery of said pump mechanism, a manually movable throttle for controlling the flow of combustion air to said engine, means responsive to the rate of flow of combustion air to said engine for operating said pump delivery control means, and manual means for operating said pump delivery control mechanism during engine starting conditions independently of said rate of air flow and independently of the position of said throttle.

15. A fuel supply system for an internal combustion engine, comprising means for controlling the rate of fuel supply to said engine, motor means for operating said control means, a manually movable control device, clutch means for connecting said manual control device to said fuel supply controlling means, means responsive to operation of said engine for operating said clutch means to disconnect said control device from said fuel supply controlling means, and time delay means for preventing such disconnection until the engine operation has continued for a predetermined time.

16. A fuel supply system for an internal combustion engine, comprising a fuel pump driven by said engine for supplying fuel under pressure, means for controlling the rate of fuel supply to said engine, motor means for operating said control means, a manually movable control device for operating said control means under starting conditions, clutch means for connecting said device and said fuel supply controlling means, means responsive to the pressure of the fuel discharged by said pump to operate said clutch means to disconnect said device from said fuel supply controlling means, and time delay means for preventing such disconnection until the pump has discharged fuel for a predetermined time.

17. A fuel supply system for an internal combustion engine, comprising means for controlling the rate of flow of fuel to said engine, fluid motor means for operating said fuel control means including a pair of expandable chambers separated by a movable wall, a source of fluid under pressure, a control valve for selectively connecting said chambers to said source to cause operation of said fluid motor means, a by-pass connection between said chambers, a valve in said by-pass connection, said by-pass valve being effective when open to terminate control of said motor means by said control valve, and means responsive to a condition of engine operation for operating said by-pass valve.

18. A fuel supply system as in claim 17, in which said fuel flow controlling means comprises injector pump mechanism, and means for varying the delivery of said injector pump mechanism.

19. A fuel supply system as in claim 17, in which said condition responsive means is responsive to the pressure of fuel flowing to said engine, and is effective when said fuel pressure falls below a predetermined value to open said by-pass valve.

20. A fuel supply system as in claim 17, including manual means for operating said fuel control means when said by-pass valve is open.

21. A fuel supply system for an internal combustion engine, comprising means for controlling the rate of flow of fuel to said engine, fluid motor means for operating said fuel control means in-

cluding a pair of expandable chambers separated by a movable wall, a source of fluid under pressure, manual means for operating said fuel flow control means, control valve means for selectively connecting said chambers to said source to cause operation of said fluid motor means, or for connecting said chambers to each other to prevent interference with said manual means by said motor means, and means responsive to a condition of engine operation for operating said control valve means.
